CIRCUIT BREAKER HOUSING FOR A ROCKET LAUNCHER

John J. Nash, Ferguson, Mo., assignor to Alesco, Inc.,
St. Louis, Mo., a corporation of Delaware

Filed Aug. 30, 1968, Ser. No. 13,345

Term of patent 7 years

Int. Cl. D13—03

U.S. Cl. D26—13

FIG. 1

FIG. 2

FIG. 3

FIG. 4

FIG. 5

FIG. 1 is a perspective view of the circuit breaker housing for a rocket launcher showing my new design;
FIG. 2 is a front elevational view thereof;
FIG. 3 is a rear elevational view thereof;
FIG. 4 is a side elevational view thereof; and
FIG. 5 is a bottom view thereof.

The dotted lines represent a rocket launcher for illustrative purposes only.

I claim:

The ornamental design for a circuit breaker housing for a rocket launcher, as shown and described.
